UNITED STATES PATENT OFFICE.

JOSEPH GOODMAN, OF WHITNEYVILLE, CONNECTICUT, ASSIGNOR TO THE MT. CARMEL MFG. CO., OF MOUNT CARMEL, CONNECTICUT, A CORPORATION OF CONNECTICUT.

METHOD OF MAKING DOOR HANDLES.

Application filed December 31, 1924. Serial No. 759,033.

This invention relates to handles and particularly to handles of the type used for automobile doors, although it is, of course, not limited thereto but may be used for making similar handles, and it has for an object to provide an improved method of mounting in these handles an insert of a contrasting color to the color of the body of the handle to give a neat and attractive appearance, and also in some instances to strengthen the handle and assist in the securing together of the parts comprising the handle.

With the foregoing and other objects in view, I have devised a method for making handles, the steps of which and articles made by this method are illustrated in the accompanying drawing, similar reference characters being employed throughout the various figures to indicate corresponding elements. In this drawing,

Fig. 1 is a side elevation of a handle complete secured to a door.

Fig. 2 is a front elevation thereof.

Fig. 3 is a transverse section substantially on line 3—3 of Fig. 2.

Fig. 4 is a longitudinal section through the handle body with the insert separated therefrom.

Fig. 5 is a similar view showing the insert placed in the body of the handle.

Fig. 6 is a transverse section substantially on line 6—6 of Fig. 5 and indicating the method of securing the insert in the handle.

Fig. 7 is a transverse section similar to Fig. 6 of a slightly different construction of handle with the insert ready for securing in position, and

Fig. 8 is a transverse section of the construction shown in Fig. 7 completed.

In Fig. 1 a portion of a door is shown at 10 having an opening 11 therein through which the latch operating spindle 12 extends, this spindle passing to any suitable type of latch not shown. The handle is secured to the door by an escutcheon plate 13 through the screws 14, and the spindle 12 extends through this escutcheon and is rotatable therein in the usual manner. This spindle is connected at its outer end to the operating handle which in the present illustration comprises a metal body member 15 having a longitudinal groove or channel 16 in its front face forming side flanges 17. When the metal body member is formed

these flanges are substantially at right angles to the body as shown in Fig. 6 or flared outwardly as shown in Fig. 7, to allow for placing of the insert 18 in the groove or channel between the flanges. The ordinary method of mounting this insert is to fill the channel in a mold with the plastic material or powdered material and vulcanizing it in the mold with the action of heat and pressure, but I have devised an improved method for placing the insert in the handle which is much less expensive and may be formed more easily and rapidly with less apparatus.

In carrying out my invention a slab or a strip 19 of the material is provided which contains approximately the amount or a somewhat greater amount than is required to fill the groove in the handle when completed, this slab being somewhat the shape shown in Figs. 4, 5 and 6 and made of a material which is hard at ordinary temperatures but is relatively soft or plastic when heated, such for instance as hard rubber. This slab is placed in the channel between the flanges 17 as shown in Fig. 6 when the hard material is heated, and therefore, is in a relatively soft or plastic condition. The flanges 17 are then pressed inwardly into the side edges of the slab by any suitable means, such as the dies 20 of a power press, to substantially the position shown in Fig. 3 so that their free edges overhang the inner side edges of the slab and are also pressed into this slab as it is relatively soft and plastic. This pressing of the flanges against the sides of the slab causes the plastic material to completely fill the groove and it is then allowed to harden by cooling, after which it is substantially in one piece with the metal bar. Any surplus material may be removed and the surface finished by grinding and polishing. The surface of the metal may be finished by nickel plating or any other suitable means, and it will be seen from an inspection of Fig. 3 that the outer surface of the insert and the metal body are continuous, giving a smooth continuous surface, and there is no possibility of the insert becoming loosened and falling out.

In Figs. 7 and 8 is shown a slightly different construction in which the insert is mounted in exactly the same way. In this

construction: the cross bar of the handle comprises a sheet metal channel member 21 with the free edges of the side members 22 providing inturned flanges 23, the channel member being secured to the latch operating spindle 24 by means of a metal bar 25 rigidly secured to the end of the spindle, as by riveting it thereto, the spindle passing through an opening 26 in the channel member. When it is first formed the cross section of the channel member is substantially that shown in Fig. 7. The insert slab 27 is placed in this channel in the heated and relatively soft and plastic condition, the sides are then pressed inwardly to the position shown in Fig. 8, firmly gripping the slab, forcing it to fill all the spaces within the channel member, and embedding the side flanges 23 in the sides of the slab as shown. The insert is then allowed to harden by cooling the same as in the first form, and may be finished by grinding and polishing. In this case, however, the insert is pressed tightly about the bar 25 and securely fastens it within the channel member, making a rigid

and strong connection between the cross bar of the handle and the spindle.

It will be apparent from the foregoing description that this method of applying the insert to the handle is much simpler than the old method of vulcanizing it in the channel, may be performed much more rapidly and with less apparatus and therefore, may be made at much less cost.

Having thus set forth the nature of my invention, what I claim is:

The method of making a door handle or the like which consists in forming the handle with a groove in its face with flanges on the opposite sides of said groove, providing in the groove a heated slab of a material which is hard at ordinary temperatures and plastic when heated, pressing the flanges against the opposite side edges of the plastic slab by pressure directed edgewise of the slab only, and allowing the slab to harden by cooling.

In testimony whereof I affix my signature.

JOSEPH GOODMAN.
